CAN OR SIMILAR ARTICLE

Dexter M. Bystedt, Clarendon Hills, and Thomas R. Stanley, Downers Grove, Ill., assignors to Continental Can Company, Inc., New York, N.Y.

Continuation of abandoned design application Ser. No. 206,986, Dec. 10, 1971. This application Dec. 4, 1972, Ser. No. 311,581

Term of patent 14 years

Int. Cl. D9—03

U.S. Cl. D9—216

FIG. 1 is an elevational view of a can or similar article embodying our new design;

FIG. 2 is an elevational view looking from the right of FIG. 1; and

FIG. 3 is a top plan view.

The characterizing features of our design reside in the configuration and appearance of the side walls as particularly disclosed in FIGS. 1 and 2.

This application is a continuation of our copending, now abandoned, prior application Ser. No. D. 206,986, filed Dec. 10, 1971.

We claim:

The ornamental new design for a can or similar article, as shown and described.
